UNITED STATES PATENT OFFICE.

JOEL L. ISAACS, OF CHICAGO, ILLINOIS

SPRAYER.

1,219,642.

Specification of Letters Patent. Patented Mar. 20, 1917.

Application filed June 29, 1916. Serial No. 106,623.

To all whom it may concern:

Be it known that I, JOEL L. ISAACS, a citizen of the United States, residing at Chicago, in the county of Cook and State of Illinois, have invented certain new and useful Improvements in Sprayers, of which the following is a specification.

The covering of various bodies with a protective coating, such as paint, varnish, and the like, by spraying the coating material thereon, has been practised for some time, compressed air being usually employed for atomizing or finely subdividing the liquid paint or varnish and discharging it under pressure in the form of a spray on the article to be treated.

Upon leaving the nozzle of the appliance, however, such spray has a tendency to expand and become more or less dissipated. In other words, upon issuing from the nozzle, the spray assumes the form of a cone with the apex at the nozzle. When large surfaces are being treated, no serious difficulty is encountered in employing a spraying or atomizing device of this character, but where relatively small parts are being treated, owing to the size of cross-section of the spray, much of the coating material is lost beyond recovery. For example, much comparatively-expensive varnish is wasted when the legs and spindles or slats of chairs and other articles of furniture are thus coated with varnish or paint because of the large percentage of varnish or paint which passes by both sides of the elements treated, and is lost.

The present invention is intended to overcome this difficulty and aims to confine or restrict the spray, that is, prevent its undue spreading, thereby facilitating its economical application to the small parts and resulting in a marked saving of the coating material used. This desirable object is reached by providing the spray nozzle with a supplemental discharge opening or nozzle through which compressed air is delivered, surrounding the spray and acting to prevent its dissipation and undue spreading. In other words, the tube, so to speak, of compressed air around the spray, confines the latter, whereby it may more advantageously be directed to the parts intended, thus restricting the size of the spray so that it can be economically employed in the coating of small parts.

In order that those skilled in this art may

have a full understanding of the invention, a desirable embodiment of the same is illustrated in the accompanying drawing which forms a part of this specification, and in 60 this drawing:

Figure 1 is a partial elevation and partial section of the device; and

Fig. 2 is a section on line 2—2 of Fig. 1.

The appliance includes a tank or chamber 10 adapted to contain the varnish, paint, or similar coating material, and it is provided with a tube 11 extending into the compartment to a point near its bottom and connected at its upper end to a nozzle or spout 12, surrounded by another 13, connected by a pipe or hose 14 to any suitable source of compressed-air, the latter nozzle being equipped with a controlling valve 15 of any suitable or desirable construction. The two 75 nozzles, 12, and 13, forming a duplex structure, may be of the usual and customary form, it being merely necessary for the compressed air issuing from the nozzle 13 to draw up the paint or varnish and discharge 80 the same through its nozzle, forming a suitable spray so that the varnish or paint is finely sub-divided and delivered from the nozzle under pressure in such condition. So far as this appliance has now been described, 85 it embodies nothing new in the art.

This duplex nozzle 12, 13, is, however, surrounded by a third nozzle or discharge appliance 16 connected by a hose or pipe 17 to a source of compressed-air, preferably, but not necessarily, of greater pressure than that in the connection 14. This outer nozzle or discharge device is also equipped with a control valve 18. The end of nozzle 16 is supplied with a sliding adjustable sleeve 19 95 which may be regulated as to position to determine the extent of its extension beyond the end of the duplex nozzle 12, 13. It will be clear that the space between the inner surface of the outer nozzle 16 and the exterior surface of the nozzle 13 is annular in form and will provide for the discharge of a similarly-shaped tube or pipe, so to speak, of compressed-air, desirably of greater pressure than that issuing from the spray-nozzle 12, 13.

This surrounding layer or stratum of air acts to confine and restrict the sprayed or atomized varnish or paint, preventing its dispersion and dissipation and adapting it 110 for the coating of articles of small size, thus doing away with the considerable loss which

has heretofore been occasioned, particularly in the varnishing of certain parts of furniture, because in those cases the varnish which passes by the sides of the small portions of the articles treated is lost and is unsuited for economical recovery. Manipulation of valve 18 varies the pressure of the air jet which will govern the spread of the spray.

10 The adjustable nozzle or surrounding sleeve 19 aids in directing the discharge of such layer of air and assists in confining and directing the jet or spray surrounded thereby.

15 To those skilled in this art it will be obvious that the invention is not limited and restricted to the precise and exact details of construction shown and described, but it will be clear that these may be modified in 20 substantial ways without departure from the heart of the invention and without sacrificing any of its substantial benefits and advantages. For example, instead of using air as the confining medium some gas suitable 25 to assist in the drying of the varnish or paint may be employed, and, if desired, heated air may be used.

I claim:

1. In an appliance of the character described, the combination of means to pro-

duce a spray, and means to confine said spray by an outer stratum or body of gas, substantially as described.

2. In an appliance of the character described, the combination of a nozzle for delivering a spray under pressure, and means to deliver gas under pressure and confining said spray, substantially as described. 35

3. In an appliance of the character described, the combination of a duplex nozzle 40 adapted to deliver a coating material under pressure in the form of a spray, and another nozzle adapted to deliver compressed-air confining said spray, substantially as described. 45

4. In an appliance of the character described, the combination of a nozzle for delivering a spray under pressure, and means to deliver gas under greater pressure than said spray, said gas confining said spray 50 and preventing its undue spreading, substantially as described.

5. In an appliance of the character described, the combination of a duplex nozzle adapted to deliver a coating material under 55 pressure in the form of a spray, and means to deliver a tube of compressed-air under greater pressure surrounding and confining said spray, substantially as described.

JOEL L. ISAACS.
